UNITED STATES PATENT OFFICE.

NATHAN S. BOYNTON, OF PORT HURON, MICHIGAN.

DESIGN FOR A BADGE.

SPECIFICATION forming part of Design No. 21,975, dated November 8, 1892.

Application filed September 2, 1892. Serial No. 444,906. Term of patent 3½ years

To all whom it may concern:

Be it known that I, NATHAN S. BOYNTON, a citizen of the United States, residing at Port Huron, in the county of St. Clair and State of Michigan, have invented a new and useful Design in Emblems, of which the following is a specification, reference being had therein to the accompanying drawing.

The following is a specification of my new and original design for a badge of the Order of the Knights of the Maccabees, reference being had to the drawing, which represents my design in elevation.

The invention relates to a new and original design for a badge.

The design is shown in the accompanying drawing, wherein it is represented as a flag in outline secured to a staff. The flag is di-

vided by vertical lines into three fields, which may be distinguished by different colors. The center field has thereon a representation of a globe with the lines of latitude and longitude thereon, and in the center of the globe is placed the representation of a tent. The outer fields may contain emblems or letters, if desired.

What I claim is—

The design for a badge, substantially as shown and described.

In testimony whereof I affix my signature in presence of two witnesses.

NATHAN S. BOYNTON.

Witnesses:

WILLIAM E. STEWART,
ALBERT A. WAGNER.
